UNITED STATES PATENT OFFICE.

IRA MARTIN HOPE, OF CHICAGO, ILLINOIS.

BOILER-CASING.

1,139,527.

Specification of Letters Patent.

Patented May 18, 1915.

Application filed September 2, 1913. Serial No. 787,980.

To all whom it may concern:

Be it known that I, IRA MARTIN HOPE, a citizen of the United States, residing at Chicago, in the county of Cook and State of Illinois, have invented new and useful Improvements in Boiler-Casings, of which the following is a specification.

This invention relates to improvements in casings or coverings for boilers and has particular application to a portable boiler casing.

In carrying out the present invention, it is my purpose to provide a boiler casing which may be readily assembled to incase 15 the boiler and conveniently knocked down to facilitate packing and transportation thereof.

It is also my purpose to provide a boiler casing or covering which will embody in its construction a number of sections designed 20 to be arranged edge to edge when assembled and each composed of a pair of plates spaced apart in parallelism, and a filler of heat insulating material interposed between the plates, each section having an open edge and 25 a closed edge, the closed edge being designed to abut the open edge of an adjacent section so that the filler contained in each section will act to effectively seal the joint between the sections thereby preventing the escape 30 of heat from the boiler.

Furthermore, I aim to provide a boiler covering of the class described which will embrace the desired features of simplicity, efficiency, durability and strength coupled 35 with cheapness of cost in manufacture, marketing and installation and which may be readily assembled and knocked down.

With the above and other objects in view, the invention consists in the construction, 40 combination and arrangement of parts hereinafter set forth in and falling within the scope of the claim.

In the accompanying drawings; Figure 1 is a view in side elevation of a stationary 45 boiler and furnace equipped with my improved casing or covering. Fig. 2 is a rear end elevation thereof. Fig. 3 is a front elevation of a hot air furnace equipped with my present invention. Fig. 4 is a perspective view of one of the sections of the casing or covering. Fig. 5 is an edge view thereof. Fig. 6 is a vertical sectional view through the end section shown in Fig. 2. Fig. 7 is a 50 fragmentary sectional view through two of the sections arranged in edge to edge contact.

Referring now to the accompanying drawings in detail, A designates a suitable base or foundation composed of any suitable material such, for instance, as brick, while B indicates a steam boiler seated upon the foundation A and adapted to receive heat from a suitable furnace C.

My improved boiler covering or casing comprises a plurality of sections 1 disposed at opposite sides of the boiler and arranged longitudinally thereof in edge to edge contact, and an end section 2 coöperating with the front wall of the furnace of the boiler to close the casing formed by the sections 1. These sections 1 rest upon the foundation A and have the upper ends thereof curved inwardly so as to incase the boiler shell, the confronting ends of the sections at the opposite sides of the boiler abutting each other. In the present instance, each side section 1 comprises a pair of plates 3, 3 spaced apart in parallelism to form a hollow section having the top, bottom and one side edge thereof closed by means of walls 4, while the remaining side edge is open and abuts the closed edge of the adjacent section. These plates may be riveted, bolted or otherwise secured in section formation and each has the upper end thereof formed with an upstanding flange 5 designed to abut the flange on the upper edge of the section at the opposite side of the boiler, the contacting flanges being formed with alining apertures to receive bolts 6 or the like. The closed edge of each section has formed at the inner side thereof a flange 7 coextensive in height with the height of the section and underlying the inner plate of the adjacent section at the open end of the latter section, while a filler 8 of asbestos or other heat insulating material fills the space between the plates of each section, and at the open edge of the same contacts with the closed end of the adjacent section and coöperates with the flange 7 on such adjacent section to seal the casing at the joint whereby the escape of heat, dust and the like from the boiler is obviated.

The end section 2 is constructed in a manner identical to the sections 1 hereinbefore described and is formed with an opening 9 from which the smoke pipe of the boiler leads and the wall of this opening 9 is formed by a ring 10 spanning the space between the plates so as to maintain the filler within the section, while below such open-

ing 9 the section 2 is provided with a door opening 11 having a wall thereof formed by a band 12 functioning in a manner identical to the ring 10, a door 13 being hingedly connected to one wall of the opening 11 so that cold air may be admitted to the interior of the casing formed by the sections when desired.

The front wall of the boiler furnace may be constructed in a manner similar to the end wall 2 of the casing, or may be of any other preferred construction. In the form of my invention herein shown, the end wall 2 of the casing is seated upon one end of the foundation A and fastened in position by means of tie rods 13'. It will be understood, however, that other suitable means may be employed to hold the end sections in proper position.

In Fig. 3 of the drawings, I have shown my improved casing or covering as applied to a hot air furnace for heating dwelling houses and the like and in this case the casing formed by the sections is spaced apart from the wall of the fire pot of the furnace so as to form an air space 14 into which cold air may be delivered and from which such air may be subsequently taken in a heated condition.

From the foregoing description taken in connection with the accompanying drawings, the construction, and manner of employing my invention will be readily apparent.

It will be seen that I have provided a casing or covering for the boilers of hot air furnaces and the like by means of which

the heat will be confined and which may be readily assembled and disassembled.

While I have herein shown and described one preferred form of my invention by way of illustration, I desire it to be understood that I do not limit myself to the precise details of construction herein described and delineated, as modification and variation may be made within the scope of the claim without departing from the spirit of the invention.

I claim:

A boiler casing comprising a plurality of sections arranged at the opposite sides of the boiler and disposed in edge to edge contact, each section comprising a pair of plates spaced apart in parallelism, and a filler of heat insulating material interposed between said plates, each section having an open edge and a closed edge, the closed edge of each section abutting the open edge of the adjacent section, flanges upstanding from the confronting top edges of the sections at the opposite sides of the boiler whereby said sections may be secured together, and a flange on the closed edge of each section and extending outwardly therefrom and underlying the open edge of the adjacent section whereby an air tight joint between the sections is effected.

In testimony whereof I affix my signature in presence of two witnesses.

IRA MARTIN HOPE.
